ATTORNEY.

UNITED STATES PATENT OFFICE.

HENRY B. BIXLER, OF AKRON, OHIO, ASSIGNOR TO THE CHILlicothe TIRE AND RUBBER COMPANY, OF CHILlicothe, OHIO.

DESIGN FOR A TIRE-TREAD.

56,217.

Specification for Design. Patented Aug. 31, 1920.

Application filed July 21, 1919. Serial No. 312,457. Term of patent 7 years.

To all whom it may concern:

Be it known that I, HENRY B. BIXLER, a citizen of the United States, residing at Akron, in the county of Summit and State of Ohio, have invented a new, original, and ornamental Design for Tire-Treads, of which the following is the specification, reference being had to the accompanying drawings, forming part thereof.

Figure 1 is a plan view of a portion of my tire tread showing my new design.

Fig. 2 is a transverse section of my tire tread, illustrating my new design in relief.

I claim:

The ornamental design for a tire tread as shown.

HENRY B. BIXLER.
